UNITED STATES PATENT OFFICE.

CALVIN H. PAINE, OF PROVIDENCE, RHODE ISLAND, ASSIGNOR TO HIMSELF,
AND HOWARD TILDEN, OF PHILADELPHIA, PENNSYLVANIA.

IMPROVEMENT IN CARRIAGE-JACKS.

Specification forming part of Letters Patent No. 36,587, dated September 30, 1862.

To all whom it may concern:

Be it known that I, CALVIN H. PAINE, a citizen of the United States of America, and a resident of Providence, in the county of Providence and State of Rhode Island, have invented a new and useful or Improved Carriage-Jack; and I do hereby declare the same to be fully described in the following specification and represented in the accompanying drawings, of which—

Figure 1 is a top view, and Figs. 2 and 3 side elevations, of my said invention, the nature of which consists, first, in a peculiar arrangement of legs and levers and in combining and arranging a toggle or link with the two levers in manner and so as to operate therewith substantially as hereinafter described.

In Fig. 2 the two levers and the toggle are exhibited in one of their extreme positions—viz., that in which they are arranged when the jack is ready to be placed underneath an axle preparatory to effecting the raising of it. Fig. 3 represents the positions of the levers and toggle when the hand-lever is depressed to its lowest situation.

The stand or frame of the carriage-jack I make of two bars, A B, crossed on one another, as shown in the drawings. The bar A is the longer one, and has a rack or notched lever, C, laid against it and the bar B, and jointed to the frame at its upper end, as shown at b.

A second or hand lever, D, is arranged underneath the lever C and between it and the bar A, and has its fulcrum E fixed on the bar B. A link or toggle, F, is jointed both to the lever C and the inferior arm a of the lever D, the whole being so constructed as to render such inferior arm and toggle a pair of toggles.

By laying hold of and pressing down the superior or longer arm of the lever D, the conjoint action of the toggle and the said lever will elevate the lever C on its fulcrum E, and this elevation of the lever C will continue until the two toggles have their joints brought into a straight line with each other. A further depression of the longer arm of the lever will throw the toggles rearward and cause the lever C to rest on the inferior arm a of the lever D, as shown in Fig. 3. Thus this carriage-jack requires no extra rack or pin to fasten its hand-lever in order to hold up the lever C. The apparatus is so constructed as to be self-fastening, and this by the downward movement of the hand-lever. The mode of making the frame and arranging it and the two levers is simple and advantageous. The lower end of each bar of the frame may be provided with a foot, c, or it may be protected by a metallic ferrule driven on it.

I lay no claim to the invention described in the United States Patent No. 30,436, granted the 9th day of October of the year 1860; but

I claim—

1. The new or improved arrangement, substantially as described, of the bars A B and the levers C D.
2. The combination and arrangement of the toggle or link F with the levers C D and their supporting-frame, the whole being made to operate as explained.

CALVIN H. PAINE.
